METHOD OF MAKING DIES

Elbert H. Porter and Fred M. Bushway, San Diego,
Calif., assignors to Solar Aircraft Company, San
Diego, Calif., a corporation of California.

Application April 23, 1945, Serial No. 589,782

3 Claims. (Cl. 22—195)

1

This invention relates to the die stamping art in which metal sheets are bent into desired shapes by pressing or striking them between dies.

An object of the invention is to simplify and reduce the cost of making dies for stamping sheet members.

Another object is to reduce the skill required in making dies for sheet stamping.

A more specific object is to provide a simple and effective way of making one die from its mating die.

Other and more specific objects and features of the invention will become apparent from the detailed description to follow, which refers to the drawing.

In making some stampings, such as half stampings of semi-circular cross-section, it is customary to use a female die, commonly referred to as the "die" and a cooperating male die which is most commonly referred to as the "punch." Obviously the punch must be smaller than the die by an amount equal to the thickness of the stamping that is to be made in the die, but because of the fact that the punch closely approaches the die in shape, many attempts have been made to form the punch from the die as a mold. However, it is necessary to compensate for the thickness of the stamping that is to be produced, and this has introduced difficulties.

One method that has been employed was to lay strips of wax in the die, the strips extending transversely across the die, and being spaced apart where the cross-section of the die changes longitudinally, after which the die was filled with plaster. After the plaster had set, it was removed from the die, and the raised portions, corresponding to the spaces between the wax strips in the die were removed by hand scraping.

Another method was to apply narrow strips of wax equal to the metal thickness along the edges of the die and fill the die with plaster. Thereafter, the main body of the plaster cast was scraped by hand to attempt to reduce its radius throughout by an amount equal to the thickness of the wax strips.

Neither of these methods has been very satisfactory for the reason that they required considerable hand work and considerable skill on the part of the worker.

In accordance with the present invention, a plaster cast can be molded, in the die, to the desired shape of the finished punch without scraping operations requiring special skill on the part of the operator. The invention is based on the principle that if the punch is lowered into contact with the bottom of the die, it will contact the latter over an area at the bottom of the die and will be spaced from the die increasing distances toward the edges. Hence, by building up the side walls of the die with wax that diminishes in thick-

2

ness toward the bottom of the die, a mold results that closely corresponds to the desired punch shape.

The practicability of the invention depends upon our further discovery of a simple and effective method of building up the side walls of the die to the desired thickness. We do this by first forming two elongated strips of sheet wax that are wedge shape in cross section and that taper from a feather edge on one side to an edge on the other side of thickness equal to the sheet metal that is to be shaped by the die. These wedge shaped wax strips are then pressed against the sides of the die with their thick edges flush with the top of the die. Because of their flexible nature, the wax strips can be readily deformed to lie against the curved sides of the die.

The die built up with wax as described is then filled with plaster, which, after it has set, is removed from the die and used as a pattern to form the punch in accordance with well known practice.

The improved method, as outlined, involves only routine operations that can be readily performed by an ordinary worker and no special skill is required such as was necessary in the processes involving the scraping of plaster casts.

Referring now to the drawing:

Fig. 1 is a cross-section showing a punch and die with a shaped metal work-piece therebetween;

Fig. 2 is a cross-section similar to Fig. 1, but showing the work-piece removed and the punch and die brought fully together;

Fig. 3 is a cross-section illustrating a method of making a wedge shape strip of wax;

Fig. 4 is a cross-section of a wedge shape piece of wax produced by the method of Fig. 3; and

Fig. 5 is a perspective view of a die that has been built up with wax, in accordance with the invention, preparatory to the casting of a plaster pattern therein.

Referring first to Fig. 1, there is disclosed a die 10 and punch 11 used for forming a half stamping, a formed half stamping 12 being shown interposed between the die and punch. The curved portion of the half stamping 12 may be exactly semi-circular in arcuate extent, although not necessarily. It is shown of exaggerated thickness in Fig. 1 to more clearly illustrate the problems involved.

It will be observed from Fig. 1 that if the work-piece 12 is of uniform thickness throughout, the curved portions of the die and punch are both of circular curvature, but the radius of curvature of the punch is less than that of the die by the thickness of the work-piece. It follows that if the work-piece is removed and the punch is fully lowered into the die, as illustrated in Fig. 2, the mid-portion of the punch will contact the mid-

3

portion of the die, and likewise the shoulders 13 of the die will be contacted by the shoulders 15 of the punch. However, the upper edges of the curved wall of the die will be spaced horizontally from the juxtaposed portions of the punch by the thickness of the work-piece, and this spacing progressively diminishes toward the bottom of the die.

In accordance with the present invention, we build up the side wall portions of the die to approximate the shape of the punch by sticking wedge shaped wax strips to the sides of the die, these wax strips corresponding in shape approximately to the spaces 16 and 17 between the punch and die in Fig. 2.

The wedge shaped wax strips may be prepared in various ways, but a convenient and practical procedure will be explained with reference to Figs. 3 and 4. Referring first to Fig. 3 a strip of wax 18, somewhat longer than the die, is laid on a flat surface 19 with one edge 20 of the wax strip overlapping one edge 21 of the surface 19, which may be determined by a table having a smooth hard top. The edge 20 of the wax is rolled slightly around the edge 21 to secure it firmly in place. A straight strip 22, of hard material such as steel is placed on top of the wax strip 18, with one edge 23 spaced from and parallel to the edge 20. The spacing between the edge 21 of the surface 19 and the edge 23 of the strip 22 depends upon the radius of the die that is to be built up, and upon the thickness of the strip 22 relative to the thickness of the work sheet that is to be formed in the die. If the strip 22 is about the same thickness as the work sheet, the distance between the edges 21 and 23 should be about twice the radius of the die. The wax strip is then reduced to a triangular cross section by moving a straight edged scraper longitudinally along the wax strip, using the upper corner of the edge 23 and the upper corner of edge 21 as limiting guides for the scraper. The cutting edge of the scraper being straight, the scraped wax strip has a beveled edge of a very small angle. The strip is then cut longitudinally to provide a strip that is wedge-shape in cross section as illustrated in Fig. 4, the width of this strip being approximately equal to the radius of the die.

Two wax strips as shown in Fig. 4 are formed and are placed in the die as shown in Fig. 5. The wax adheres to the wall of the die and is readily deformed to assume the curvature of the die. Thereafter, the die is filled with plaster, which is allowed to set and is then removed from the die and used as a pattern to prepare the finished punch in accordance with well known foundry practice.

If the die is of uniform cross-section longitudinally, the wedge-shaped wax strips can be placed in the die intact. On the other hand, if the die has a curved upper surface, as illustrated in Fig. 5, it is desirable to make cuts or serrations 25 in the thin edges of the wax strips to allow the upper edge to conveniently follow the curve. Of course these cuts or serrations 25 produce ridges in the plaster cast, but the ridges are of such small area that they can be quickly and easily scraped down flush with the general surface of the cast.

The wax strips formed as described do not correspond exactly in thickness and width to the

4

thickness and width of the spaces 16 and 17 in Fig. 2. The strips of Fig. 4 have a thickness varying linearly from the thin to the thick edge, whereas the variation in thickness of the spaces 16 and 17 is not linear, and their width is greater than the width of the strips. However, it is found in practice that where the workpiece is from .016 inches to .030 inches thick, it is satisfactory to make the wax strips of width equal to an arc of about 30° in the die. For workpieces of thickness between .030 and .100, it is satisfactory to make the wax strips of width equal to an arc of about 60° in the die. Such strips, even though they vary in thickness in linear relation as shown in Fig. 4, produce punches that compare favorably in accuracy with the best punches that are producible by prior known methods and that can be made at a cost substantially less than the cost of producing punches by the most satisfactory prior methods.

Although for the purpose of explaining the invention, it has been described in detail with reference to a die for making a half stamping of semi-circular cross-section, its utility is not limited to dies of circular curvature, but is applicable generally to dies having relatively steep side walls and relatively flat bottoms.

We claim:

1. In the art of sheet stamping pieces of curved cross-section, the method of making a pattern for a complementary die from a first die of said curved cross-section comprising: preparing two strips of deformable material, each of width less than the depth of said first die and tapering laterally in thickness from the thickness of the work sheet to be stamped at one edge to a feather edge at the other edge, securing said strips against the opposite side walls of said first die with their thick edges flush with the edges of the die, and using said built up first die as a mold for casting the pattern for the complementary die.

2. The method described in claim 1 in which said deformable material is wax.

3. In the art of sheet stamping, the method of making a pattern for a punch for use with a die of approximately semi-circular cross section, comprising: building up the side walls of the die by an amount that is uniform longitudinally but that tapers from the thickness of the sheet to be stamped at the edges of the die, to a feather edge at points intermediate said edges and the bottom of the die, and using said built-up die as a mold for casting the pattern for the punch.
